UNITED STATES PATENT OFFICE.

HORACE T. THOMAS, OF LANSING, MICHIGAN.

PISTON.

Application filed May 7, 1921. Serial No. 467,733.

To all whom it may concern:

Be it known that I, HORACE T. THOMAS, a citizen of the United States, residing at Lansing, county of Ingham, State of Michigan, have invented a certain new and useful improvement in Pistons, and declare the following to be a full, clear, and exact description of the same, such as will enable others skilled in the art to which it pertains to make and use the same, reference being had to the accompanying drawings, which form a part of this specification.

My invention relates to pistons for engines and an object of my improvements is to provide an improved piston for internal combustion engines and one in which the piston pin shall not become loose. I secure this object in the device illustrated in the accompanying drawings, in which:

Figure 1 is a section of a piston embodying my invention.

Fig. 2 is a detailed sectional view to an enlarged scale of a part of the device of Fig. 1 illustrating its mode of operation.

Fig. 3 is an inverted detailed plan view of a part of said apparatus.

a is the piston having the usual transverse aperture *a*² for the reception of the piston pin. *b* is the piston pin in this case shown as tubular. *b*² *b*² are co-axial apertures through the wall of the piston *b* toward one end thereof.

c is a pin having a screw threaded part *c*³ of larger diameter, and a part of smaller diameter extending from the part *c*³. *c*² is a conical wall upon the pin *c*. *b*³ is a concave conical portion of the wall at the lower part of the lower aperture *b*².

*c*⁴ is the square head at the lower end of the pin *c*. The pin *c* engages with its screw threaded portion *c*³ in an aperture through a portion *a*⁵ of the piston *a*. The portion of said pin of smaller diameter passing through the holes *b*² *b*² and engaging in a portion *a*⁴ of the piston *a* above the piston pin *b*. The conical portion *c*² of the pin *c* engages against the conical wall *b*³ of the lower aperture *b*².

d is a coil spring surrounding the pin *c* towards its lower end. The lower spire of the spring *d* is made rectangular as shown in Fig. 3 so as to fit over the square portion *c*⁴ of the pin *c* and the ends of the spring *d* are extended to engage the wall of the piston pin upon opposite sides of the pin *c* as

shown at *d*² *d*³. *a*³ is an annular ridge extending around the inner wall of the piston *a* at its open lower end. The end *d*³ of the spring *d* engages above the annular ridge *a*³ to hold said spring in its position.

The relative size and location of the parts are such that in their normal position the square spire *d*⁴ of the spring *d* engages over the square end *c*⁴ of the pin *c* to lock said pin.

s is a socket wrench adapted to engage over the head *c*⁴ of the pin *c*.

The operation of the above described device is as follows:

To adjust the parts the socket wrench is engaged over the head *c*⁴ of the pin *c* as shown in Fig. 2 pressing the spire *d*⁴ to a position above the square head *c*⁴. The pin is then turned by the wrench until the conical portion *b*³ is pressed firmly against the conical wall of the lower aperture *b*² of the pin *b*, thus clamping said pin in position and holding it firmly. When the socket wrench *s* is removed the spire *d*⁴ of the spring *d* again engages over the square head *c*⁴ and locks the pin in its position.

The engaging walls of the pin *c* and the aperture *b*² are at an angle to the center line of the piston pin so that the latter is firmly held against both longitudinal and transverse motion.

Claims:

1. The combination of a piston, a piston pin, a screw threaded locking pin for securing said piston pin, said locking pin having a squared head adjacent to the open end of said piston and adapted to be engaged by a wrench, a spring adapted to automatically engage over the squared end of said pin to hold the same from rotation, said spring being adapted to be pressed out of engagement with the squared end of said pin by the engaging wrench, said piston being provided with an annular ridge around the open end, said spring having a prong engaging over said ridge to prevent the spring from falling away from said pin.

2. The combination of a piston, a piston pin, a screw threaded locking pin for securing said piston pin, said locking pin having a squared head and adapted to be engaged by a tool for turning said pin, a spring adapted to automatically engage over the squared end of said pin to hold the same from rotation, said spring being adapted to

be pressed out of engagement with the squared end of said pin by the engaging wrench.

3. The combination of a piston, a piston pin, a screw threaded locking pin for securing said piston pin, said locking pin having a squared head and adapted to be engaged by a tool for turning said pin, a coil spring surrounding said locking pin and having a spire adapted to automatically engage over the squared end of said pin to hold the same from rotation, said spring having a part thereof extending outward and engaging the piston to prevent the rotation of said spring about its longitudinal axis.

4. The combination of a piston, a piston pin, a screw threaded locking pin for securing said piston pin, said locking pin having a squared head and adapted to be engaged by a tool for turning said pin, a coil spring surrounding said locking pin and having a spire adapted to automatically engage over the squared end of said pin to hold the same from rotation, the ends of the wire of which said spring is made extending outward at an angle in opposite directions and engaging the piston wall to prevent the rotation of said spring about its longitudinal axis.

5. The combination of a piston, a piston pin, a screw threaded locking pin for securing said piston pin, said locking pin having a squared head and adapted to be engaged by a tool for turning said pin, a coil spring

surrounding said locking pin and having a spire adapted to automatically engage over the squared end of said pin to hold the same from rotation, the ends of the wire of which said spring is made extending outward at an angle in opposite directions and engaging the piston wall to prevent the rotation of said spring about its longitudinal axis, said spring being adapted to be pressed out of engagement with the squared end of said pin by the engaging wrench.

6. The combination of a screw threaded pin, a coil spring surrounding said pin, said pin having a head, said spring having a spire adapted to automatically engage said head to prevent the relative rotation of said pin and spring and means for preventing the rotation of said spring with said pin.

7. The combination of a screw threaded pin, a coil spring surrounding said pin, said pin having a head and adapted to be engaged by a tool for turning said pin, said spring having a spire to automatically engage said head to prevent the rotation of said pin and means for preventing the rotation of said spring with said head, said spring being adapted to be pressed out of engagement with the head of said pin by a tool engaging said pin to turn the same.

In testimony whereof I sign this specification.

HORACE T. THOMAS.
